DRAFT KEY RETAINER LOCK

Edward Payson Smith, Winnetka, Ill., assignor to Illinois Railway Equipment Company, Chicago, Ill., a corporation of Illinois

Application June 22, 1950, Serial No. 169,560

3 Claims.

(Cl. 85—5)

1

My invention relates to a device for holding the standard T-type retainer in the draft keys of railroad car draft rigging in place against accidental removal without, however, in any way interfering with the necessary free movement of the draft keys; namely, a device which obviates the need of the usual cotter pin and therefore complies with the Association of American Railroads requirements for means, other than the usual cotter pin, whereby the retainer will be locked against undesirable vertical movement and ultimate loss of the draft key retainer and possible loss of the draft key.

The invention also has for its object, the provision of a locking or holding device which will provide a full bearing on the retainer and also compensate for the necessary and desired angling of the retainer and movement of the draft key, while obviating the need for employing or supplementing the usual cotter pin.

The objects and advantages of my invention will all be readily comprehended from the following detailed description of the accompanying drawings wherein:

Figure 1 is a plan view of a portion of a draft key and the standard T-type retainer, with my improved locking means; a portion of a center sill being shown in section.

Figure 2 is an end view, as viewed from the lower end of Figure 1 with the locking means applied and the portion of the center sill omitted.

Figure 3 is a side elevation of the structure shown in Figure 2.

Figure 4 is a perspective view of my improved locking means.

My improved locking means as exemplified in the drawings is intended for use with the A. A. R. standard draft key shown at 10 for associating the draft rigging with the usual car center sill beams; a portion of one being shown in section at 11 in Figure 1; the draft key passing through suitable slots in the sills; the slots being of length somewhat greater than the usual width of the key to permit proper play and operation of the springs of the draft rigging. The T-type draft key retainer is indicated at 12 and consists of a large pin portion or shank 12 of length sufficient to pass through the heavy draft key 10, and the pin portion is usually provided with a transverse hole to receive the usual cotter pin shown at 13; while the upper end of the pin has an elongated head 14 which normally is intended to extend transversely of the draft key as shown with one of the flat sides of the head arranged substantially parallel with the center sill 11.

As previously stated, the purpose of my improved retainer lock is to hold the retainer in proper position against vertical upward movement out of the draft key while at the same time permit necessary angling or desired partial normal rotation during train operation without, however, getting into a jamming relation with the car center sill.

My improved locking means consists of a single piece member or forging 15 having a vertically disposed body portion 16 which slopes toward opposite sides from the vertical median line, particularly on the retainer facing side as more clearly seen in Figures 1 and 4, to provide flat bearing surfaces for the retainer during angling conditions. The top of the body portion 16 has an overhanging head or flange 17 disposed toward the retainer head facing side of the lock member and said head or flange 17 is adapted to overlie the retainer head 14 as shown in Figures 1 and 3.

The opposite or outer side of the lock member 15, at the base of the main body portion 16 is provided with a flange 18, shown extending substantially parallel with the head or flange 17 and at right angles to the body portion and disposed toward the tail end of the draft key 10 on which it rests.

The distance between the head flange 17 and flange 18 preferably is made greater than the thickness of the head 14 of the standard retainer so as to maintain the head 17 out of pressing contact with the top 14 of the retainer, as more clearly shown in Figure 3, when the lock member is in fully applied position and thus not subject the retainer to frictional pressure which would interfere with the desired normal or free rotary movement of the retainer induced by the retainer contacting the side of the center sill 11 caused by the car going around a curve.

The opposite ends of the body portion 16 terminate in the two vertical or downwardly extending pins or legs 19, 19, preferably cylindrical as shown in Figure 4 and of length sufficient to extend entirely through the comparatively thick bar or draft key 10 and extend therebeneath as seen in Figure 3 and permit the exposed ends to be spread or slightly bent, after assembly as shown at 19a in Figure 2, thereby securing the lock member in locking position against upward vertical movement.

The lock is adapted to be used with the standard type draft key partially shown at 10, by merely drilling or providing the tail end of the key 55 between the usual retainer pin receiving hole and

the distal end with a pair of comparatively small holes arranged equal distances on opposite sides of the longitudinal median line of the draft key and adapted to receive the legs 19, 19 of the lock member. That is to say, my improved lock member is adapted to be used with the standard type draft key without modification in the latter except for drilling or providing the two holes just mentioned.

As is apparent from the lock construction, the two spaced apart legs will prevent any rotary movement on the part of the lock, while the retainer facing oppositely sloping sides of the lock permit the retainer to have the required degree of rotary movement when the car is going around a curve; the oppositely sloping faces act as stops against the too far or ninety degree rotation of the retainer where its head would contact and become wedged against the center sill with the possibility of being sheared off.

The outwardly facing flange 18 provides a relatively large area which rests on the draft key and tends to decrease wear and at the same time it limits the downward movement of the lock member and in the event the lock member is reversely applied, the flange 18 would engage the top of the retainer head and prevent the lock member from seating properly and the legs from projecting through the draft key, thereby indicating to the operator that the lock member is improperly applied.

I have shown and described what I believe to be the best adaptation of my invention, but structural modifications are possible and may be made without, however, departing from the spirit of my invention as defined in the appended claims.

What I claim is:

1. A draft key retainer lock comprising a vertical body portion provided on opposite sides of the vertical median line with oppositely sloping faces on its retainer facing side and a laterally disposed head portion adapted to overhang the head of the retainer, the body portion at opposite ends having depending legs of predetermined length adapted to pass through openings 45 in the draft key intermediate the retainer receiving opening in the draft key and the tail end thereof and to extend therebeneath, the lower ends of said legs being bendable laterally, where-

by rotary movement of the lock member and vertical movement of the retainer are prevented and a predetermined degree of rotative movement permitted.

5 2. A draft key retainer lock forging provided at the top with a laterally disposed head portion adapted to overlie the retainer head and prevent upward movement of the retainer and the head portion on its side having oppositely sloping retainer facing surfaces adapted to separately contact the retainer and provide wide bearing relation whereby the retainer is restricted to prescribed rotary movements, the lower part of the member having laterally spaced draft key pin portions adapted to pass through the draft key.

15 3. The combination, with a draft key provided with an opening adjacent its tail end therethrough, a retainer for the key insertable through said opening and having an elongated head and a

20 pair of laterally spaced openings in the draft key intermediate said retainer-receiving opening and the tail end of the key, of a retainer lock member consisting of a body portion having oppositely sloping retainer head-engaging surfaces on opposite sides of its vertical median line separately engageable with the retainer head during angular movement, said body portion having at top a laterally disposed flange adapted to overlie the retainer head and a rearwardly disposed flange portion at a distance removed somewhat greater than the thickness of the retainer head so as to normally maintain the first mentioned flange out of immediate contact with the retainer head, the body portion of the lock member having a pair 25 of laterally spaced depending elongated pin portions of length adapted to extend entirely through said pair of openings of the draft key so as to depend therebeneath, the lower ends of said depending pin portions being laterally bendable to prevent vertical removal of the lock member.

EDWARD PAYSON SMITH.
